US0D1087006S

(12) **United States Design Patent** (10) **Patent No.:** **US D1,087,006 S**
(45) **Date of Patent:** **** Aug. 5, 2025**

(54) **FOLDABLE CHARGER**

(71) Applicant: **SARIANA, LLC**, San Diego, CA (US)

(72) Inventor: **Mustafa Burak Guclu**, San Diego, CA (US)

(73) Assignee: **SARIANA LLC**, San Diego, CA (US)

(**) Term: **15 Years**

(21) Appl. No.: **29/879,265**

(22) Filed: **Jul. 5, 2023**

(51) LOC (15) Cl. **13-02**

(52) U.S. Cl.

USPC **D13/108**

(57) **CLAIM**

The ornamental design for a foldable charger as shown and described.

DESCRIPTION

FIG. 1 is a top, front, and right perspective view of a foldable charger showing our new design fully open;

FIG. 2 is a bottom, rear, and left perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof;

FIG. 8 is a rear elevational view thereof; and

FIG. 9 is a top, front, and right perspective view of the foldable charger shown fully closed;

FIG. 10 is a bottom, rear, and left perspective view thereof;

FIG. 11 is a top, front, and left perspective view thereof;

FIG. 12 is a top, front and left perspective view of the foldable charger shown fully open and in a first environment of use;

FIG. 13 is a top, front, and left perspective view of the foldable charger shown in a partially folded state; and,

FIG. 14 is top, front, and left perspective view of the foldable charger shown in a partially folded state and in an environment of use.

The broken lines showing a mobile phone, case, and smart watch in FIGS. 12 and 14 depict environmental structure and all other broken lines depict portions of the foldable charger that form no part of the claimed design.

1 Claim, 12 Drawing Sheets
